DAVID P. SAWYER, OF CLEVELAND, OHIO, ASSIGNOR TO ECONOMY PRODUCTS CORPORATION, OF CLEVELAND, OHIO, A CORPORATION OF OHIO

CAN-OPENING APPARATUS

Application filed February 14, 1925. Serial No. 9,123.

This invention, as indicated, relates to a can opening apparatus. More particularly, it comprises a machine having a stationary cutter and means adapted to rotate a rim of 5 the can about said cutter.

Can opening apparatus of the general character herein referred to has been known heretofore, but in many such devices the construction is complicated and expensive to 10 manufacture. Furthermore, no provision is made for firmly gripping the rim of the can to be opened and reliability of operation does not result.

The principal object of the present invention is to simplify the construction of apparatus of the character described and to provide a device which will be free of the disadvantages referred to. Another object of the invention is to provide an apparatus 20 having a minimum number of parts and adapted to be readily assembled and maintained in accurate working adjustment. Other objects of the invention will appear in the course of the following description. 25 To the accomplishment of the foregoing and related ends, said invention, then, consists of the means hereinafter fully described and particularly pointed out in the claims.

The annexed drawing and the following 30 description set forth in detail certain mechanism embodying the invention, such disclosed means constituting, however, but one of various mechanical forms in which the principle of the invention may be used.

35 In said annexed drawing:—

Fig. 1 is a side elevation of an improved apparatus embodying the principle of my invention shown as applied to the edge of a support with the can in position thereunder; 40 Fig. 2 is a rear elevation of the device shown in Fig. 1, as seen from the left-hand side; Fig. 3 is a central vertical sectional view through the head of the apparatus showing the parts in retracted position; and Fig. 4 45 is a view similar to Fig. 3 showing the parts in operative engagement with the top edge of the can.

As is clearly shown in the drawing the apparatus comprises a standard 1, having integrally formed therewith a head block 2

which connects the upper ends of a bifurcated or yoke section 3 formed on said standard. The lower end of said standard is slidably engaged in the rearward portion of the clamping plate 4, being held in adjusted position thereto by means of a set screw 5 at the rearward edge of said clamping plate. The clamping plate has an upper extension plate 6 of a size suitable to support the base of the can to be operated upon, and has an extension arm 7 beneath said extension plate, through which a clamping screw 8 is adapted to operate and thereby secure the apparatus upon some suitable point of support, such as a shelf or table edge. 55

The head block is centrally apertured to provide a passageway 11, within which a cylindrical journal block 12 is loosely engaged. Said journal block is centrally apertured to receive a spindle 13, which at its lower end is provided with a squared section 14 adapted to receive the toothed can rotating wheel 15, being held thereto by means of a retaining screw 16 and lock washer 17. The upper end 18 of the spindle is provided with flattened sides and is provided with a transverse aperture 19 adjacent its upper end. A crank arm 21, having a knob or handle 22 at one end and provided with a bifurcated cam head 23 at its opposite end, is secured to the upper end of said standard by means of a pin 24. 65

Between the top surface of the head block and the bifurcated cam 23 a cutter supporting plate or table 25, centrally apertured to fit over said spindle, is positioned. The central under side of said plate is adapted to bear against a coil spring 26, the lower end of which rests upon a washer 27 of a size somewhat larger than the diameter of the journal block. The plate 25 is provided at diametrically opposite points with openings 31, 32, one serving as the point of support for the cutter mechanism and the other being adapted to receive the screw threaded end of a cam plunger bar 33. An integral boss 34 is preferably formed upon the under side of said plate adjacent the opening for the cam plunger bar so as to provide a screw threaded socket, affording a wide range of adjustment 70 75 80 85 90 95 100

for said plunger bar. The means for supporting the cutter comprises a screw stud 35 engaged through the opening 31 and held firmly therein by means of a lock nut 36. 5 The lower end of said screw stud is adapted to be engaged by a screw threaded cylindrical collar 37 and held in any desired position of adjustment by means of a lock nut 38. The lower end of the stud projects only a short 10 distance through the central opening of said collar, and the lower portion of said opening is adapted to receive the upper end or shank 41 of the cutter. A transverse opening is provided through said collar, within 15 which a set screw 42 is engaged, said set screw being adapted to clamp the cutter in any desired position of adjustment. In alignment with the set screw the cutter supporting collar is provided with a laterally 20 extending guide pin 43, said pin having one end firmly set into the transverse opening in said collar and having its free end provided with an upwardly beveled face 44.

The head block is formed with a pair of 25 vertical openings 45, 46 on opposite sides of the central opening and parallel thereto to receive respectively the cutter supporting members and the plunger bar. The opening 45 is preferably a cylindrical opening of a 30 diameter suitable to slidably receive the cutter supporting collar 37, and at its lower end connects with an opening 47 of reduced diameter, through which the lower end of the cutter is adapted to be projected. The 35 opening 45 is provided with diametrically opposite vertical slots 48, 49, which afford passageways within which the set screw 42 and the guide pin 43 are received, respectively.

40 The opening 46, within which the plunger bar is adapted to be received, communicates at its lower end with a radially disposed cylindrical opening 51 formed adjacent the lower end of the head block. Within said 45 opening a slidable cylindrical cam block 52 is engaged, said block having a projecting stud 53 formed centrally of its head portion and having an inclined cam face 54 at its base. A cylindrical plug 55 is adapted to 50 close the radial cylindrical opening 51.

The journal block 12, in addition to having the axial passageway forming a bearing for the spindle 13, is provided upon one side with a vertical slot or groove 56 of a size suitable 55 to receive the projecting beveled end of the guide pin 43, and at a point slightly below its mid-length is formed with a radial opening 57 connecting with said vertical groove 56 in a position to be engaged by the beveled 60 end of the guide pin when said cutter is projected in operative position below the head block. Said journal block is provided with a second radial opening 58 upon the opposite side from the opening 57 and at a point 65 slightly below the same, which is of a size

adequate to receive the stud 53 formed on the head of the cam block 52.

When the parts above described are assembled the cam block 52 is engaged with its opening before the plunger bar 33 is adjusted to its operative position, inasmuch as the lower end of the plunger bar would otherwise prevent the cam block being inserted through the radial opening 51 before the cylindrical plug 55 is put in place. The operation of the device has been partly indicated in connection with the description of its construction. 70

When the proper adjustment of the plunger bar is secured the depression of the cam plate, through the action of the cam head of the crank arm, will serve to force the cutter downwardly, and as the head of the guide pin rides into the transverse opening 57 the beveled end of the plunger bar will contact with the cam face of the plunger 80 85 90 95 100 105 110 115 120 125 130 block 52 and force the spindle and the can rotating gear toward the inner side of the cutter. Thus, when a can is placed in position beneath the head block with its upper side portion bearing against the toothed can rotating wheel, and the crank arm is lowered by means of the knob 22 to a substantially horizontal position, the cutter will be forced through the top of the can and the lower end of the spindle will be moved toward said cutter so as to firmly grip the adjacent portion of the cam between the side of the cutter blade and said can-rotating wheel. Rotation of the crank arm then causes the can to be rotated against the cutter and the knife edge of the cutter opens the top sheet of the can adjacent the rim, bending the metal back against the side wall of the can and permitting full access to the contents of the can as the opening is carried to the desired extent. The head block may be readily adjusted to accommodate cans of any type by merely loosening the set screw 5 and readjusting the height of the standard accordingly.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A can-opening device comprising a support, a vertical spindle rotatably mounted in said support, a toothed wheel carried by the lower end of said spindle, a crank handle pivoted to the upper end of said spindle for rotating the same, a cutter reciprocably associated with said support, means on said crank handle for moving said cutter downwardly beneath said support, means permitting said toothed wheel and cutter to be moved toward each other before said cutter

has reached its limit of downward motion, and cam means for moving said wheel toward said cutter.

2. A can-opening device comprising a support, a vertical spindle rotatably mounted in said support, a toothed wheel carried by the lower end of said spindle, a crank arm pivotally secured to the upper end of said spindle for rotating said toothed wheel, a cam block operatively associated with said spindle, a plate associated with said support and movable toward and away from same, a cutter and cam member carried by said plate, a combined cam and crank handle for moving said plate toward said support to engage the cutter with the top of the can and moving said cam bar against said cam block to force said spindle toward said cutter and said toothed wheel into clamping engagement with the side wall of the can.

Signed by me, this 11th day of February, 1925.

DAVID P. SAWYER.
